TOOLHOLDER

Arthur W. Poreau, Middletown, R. I., assignor to
McCrossy Tool Corporation, Meadville, Pa., a
corporation of Pennsylvania

Application August 11, 1942, Serial No. 454,449

8 Claims.

(Cl. 29—49)

The present invention relates to improvements in tool holders for lathes or the like, and more particularly to guard mechanism for such holders.

In the operation of lathes such as those used in metal turning operations, difficulty is often experienced due to the presence of fine chips and pieces of metal from certain types of work which often work under the tool holder or turret and interfere with the holder or turret mechanism.

An important object of this invention is the provision of a guard mechanism to prevent metal pieces or other foreign matter working under the tool holding mechanism.

Another object of the invention is the provision of a guard mechanism of this character which will permit free movement and operation of the tool holding turret.

A further object of the invention is to provide a device of this character which is automatic in operation and which may be readily attached to tool holders in use or applied to tool holders during manufacture.

Still another object of the invention is the provision of a device of the above mentioned character which is of simple construction and operation, which is inexpensive to manufacture and install, and which will not interfere in any way with the normal operation of the tool holder or turret.

Other objects and advantages of the invention will be apparent during the course of the following description.

In the accompanying drawings, which form a part of this specification, and wherein like numerals designate like parts throughout:

Figure 1 is an elevation of a tool holding turret having my invention applied thereto;

Figure 2 is a top plan view thereof;

Figure 3 is a fragmentary elevation showing the operative position of the guard mechanism;

Figure 4 is a fragmentary perspective view of the turret during rotation and illustrating the action of the guard plates during adjustment of the tool turret;

Figure 5 is an elevation similar to Figure 1 with parts shown in section to disclose the operative position of two of the guard plates and illustrating the turret indexing mechanism;

Figure 6 is a bottom plan view of the turret body with the indexing column removed;

Figure 7 is a fragmentary detail view, partly in section, showing one position of one of the guard plates, and

Figure 8 is a similar view showing another position of one of the plates.

In the drawings, wherein for the purpose of illustration is shown a preferred embodiment of the invention, the numeral 10 designates the body of a tool holding turret having an upper horizontal flange 11 and a lower horizontal flange 12. The flanges 11 and 12 extend about the perimeter of the body 10 and suitable bolts 13 extend vertically through the upper flange 11 to engage the tools 14, which are disposed between the two flanges, to removably secure the same in position. While only one tool is illustrated in Figures 1 and 2, a plurality of such tools 15 are employed, depending upon the type of work to be done, and upon the type of turret used.

A circular bore 15 extends axially through the body 10 from top to bottom thereof and a large circular recess 16 is disposed concentrically about the bore on the bottom of body 10. A series of tooth-shaped notches 17 are disposed about the periphery of the recess to form teeth 18. The notches are shown as twelve in number although any suitable number may be employed. A handle 19 is secured to the top of the body 10 by means of a collar 20 which permits relative rotation between the handle and body but prevents movement of the handle away from the body 10.

The stationary base 21 of an indexing column 30 is adapted to fit within the recess 16 and has teeth adapted to mesh with the teeth 18. The column extends upwardly through the bore 15, and has its upper portion provided with a steep square cut thread 22, the threaded portion of the column extending a substantial distance above the body 10. The handle 19 is provided with a bore aligned with bore 15 and having an internal thread complementary to thread 22 on the column. The indexing column has an axial bore to receive a bolt 23 which extends completely through the column and carries a cross member 24 at its lower end adapted to be slidably received in the horizontal portion of a T-slot 25 extending from end to end through the compound rest 26. A nut 27 engages the threaded upper end of bolt 23 and when it is tightened in place, it locks the body and column in position and by binding the cross member in the slot 25 it secures the column in adjusted position on the rest 26.

A cam 28 is secured to the top of the column and fits within a notched portion of the handle 19. A spring pressed plunger 29 normally engages in a recess 30 in the cam to lock the handle 55 in position. A sleeve 31 surrounds the lower por-

tion of the column within bore 15 and has a series of vertical notches aligned axially with the indexing notches on the column base and cooperating with a spring plunger 32 extending into the bore 15.

The column and base 21 are locked in adjusted position by bolts 23 and nut 27. When it is desired to change the index setting of the tool carrying body 10, the handle 19 is rotated by moving plunger 29 out of the recess 30 in cam 28, and this rotation of the handle acts through thread 22 to bodily raise the handle and body 10. The column and base 21 cannot rise with the body, due to bolt 23, and consequently the notches 17 are raised out of contact with the indexing teeth on base 21. The body 10 may then be rotated about the column to the desired position and lowered by a reverse rotation of handle 19 so that notches 17 again receive the teeth on base 21, to lock the body in its adjusted position. The body and tool are then in position for the desired operation.

The turret mechanism thus far described is of well-known construction, being of the "McCrosky" type, and need not be further described here. The turret construction shown and described is for convenience of illustration, and it is not intended that the guard mechanism of this invention be restricted to use on this particular turret, index mechanism or rest 26 as it may obviously be used on other kinds of turrets or tool holders.

In the operation of tool holders or turrets of the general type illustrated, it has been found in practice that in certain types of work the cuttings or chips will be sufficiently fine to work in between the bottom of the body 10 and the top of the rest 26 and interfere with the accurate functioning of the indexing notches and teeth. This is highly objectionable because the tools must be held in the proper position to insure accurate work. It is the purpose of this invention to prevent passage of chips or other foreign material between the tool holder and the rest 26.

As indicated in Figures 1, 2 and 5, the turret body with flanges included is square and has a width corresponding to the width of the rest 26 which is shown as being longer than the turret body. Each side of the body flange 12 is provided with a guard plate 33 of the same length as the body flange and of substantially greater height. Each plate 33 is provided adjacent each end with an elongated vertical slot 34. A bolt 35 extends through each slot in a horizontal direction and is embedded in or otherwise secured to the outer face of the body flange 12, as by means of screw threads as indicated in Figures 7 and 8. The bolts 35 may have removable nuts 36 for heads, as indicated in the drawings, or may have integral heads. The bolts 35, or the nuts 36 are so adjusted that the plates 33 are free to move vertically. The slots 34 limit the vertical movement of the plates. In the lower position of the plates, they extend a substantial distance below the bottom of the body 10 and below the upper edge of the rest 26 as indicated in Figures 1, 3, 5 and 7. In their upper position the plates are disposed above the top of the rest 26, as indicated particularly in Figures 4 and 8.

An important feature of the plates is that their lower corners are rounded to provide cam surfaces 37 at each lower end of each plate. The

longitudinal edges of the rest 26 are also rounded at 38, as is customary.

In the normal operating position of the turret, two opposite plates 33 will be in their lower 5 positions indicated in Figure 7 and will extend down along the side of the rest 26, effectively covering the slight space 39 between the bottom of the body 10 and the top of rest 26. This space 39 is exaggerated in the drawings, for the purpose of illustration. The other two plates 33 10 will be in a raised position, indicated in Figure 8 with their bottoms resting upon the top of the rest 26. The weight of the plates will insure a close engagement of the plate with the top of 15 the rest and prevent passage of any foreign material.

When the turret body is rotated to bring another tool into position, or for any other purpose, the rounded cam surfaces of the plates 20 in the lower position will engage the rounded top edge of the rest and raise the plates to permit their passage across the top of the rest 26. The raised position of the plates during rotation of the turret is indicated in Figure 4. Due to the cam surfaces 37 and 38, the plates will be automatically raised and will not require manual control.

It will be seen that the plates 33 may be readily attached to tool holders or turrets and will 30 effectively prevent passage of cuttings, chips or other foreign matter. The guard plates may be used with various types of tool holders and with other types of rests, and when applied to a tool holder they do not require any attention by the 35 operator.

Having thus described my invention, what is claimed is:

1. In a device of the character described, a 40 rest, a tool holder adjustably mounted on the top of the rest, and a guard plate movably carried by the tool holder and adapted to extend below the top of the rest in one position and to be disposed above the top of the rest in another position, and said rest and said guard plate having means which cooperate upon adjustment of the tool holder on the rest to raise the guard plate from its lower position to its higher position above the rest.

2. In a device of the character described, a 50 rest, a tool holder rotatably mounted on the top of the rest, a guard plate disposed along one side wall of the holder in a substantially vertical position, and means connecting the tool holder and guard plate and permitting sliding movement of the guard plate vertically from a position in which the plate extends below the rest to a position in which the plate is disposed entirely above the rest, said connecting means comprising a bolt and a cooperating vertically elongated slot, and said rest having means which upon rotation of the tool holder on the rest engages and raises the guard plate from its lower position to a position above the rest.

3. In a device of the character described, a 60 rest, a tool holder rotatably mounted on the top of the rest, a guard plate disposed along one side wall of the holder in a substantially vertical position, and means connecting the tool holder and guard plate and permitting sliding movement of the guard plate vertically from a position in which the plate extends below the rest to a position in which the plate is disposed entirely above the rest, said guard plate being freely movable from its lower position to its higher position, and said rest having cam means

which upon rotation of the tool holder on the rest engages and raises the guard plate from its lower position to a position above the rest.

4. In a device of the character described, a rest having a rounded upper edge, a rectangular tool holder rotatably mounted on the top of the rest, and a guard plate disposed along the lower portion of each side of the holder in a substantially vertical position, each guard plate being connected to the tool holder by a sliding connection permitting movement of said plate vertically from a position in which the plate extends below the rest to a position in which the plate is disposed entirely above the rest, said guard plates being freely movable from their lower positions to their higher positions, the lower corner of each plate being shaped to form a cam surface for engaging the rounded upper edge of the rest to raise the plate from its lower position to a position above the rest when the tool holder is rotated with respect to the rest.

5. The combination with a tool holder adjustably mounted on a rest having a rounded upper edge, of a guard plate carried by the tool holder adjacent one edge thereof, said plate having one position in which it extends below the top of the rest and another position at which it is disposed above the top of the rest, and said plate having a cam surface to engage the rounded upper edge of the rest for raising the plate when the tool holder is adjusted with respect to the rest.

6. In a device of the character described, a rest, an indexing column secured to said rest and having a corrugated indexing base supported on said rest, a rectangular tool holding turret rotatably mounted on said column and having its lower portion provided with corrugations to engage and mesh with the corrugations of the indexing base, means to move said turret out of operative engagement with the indexing base, and guard plates carried by the lower portions of the sides of the turret, said plates being independently movable vertically from a position in which they extend below the top of the rest to a position in which they are disposed above the top of the rest, said plates being connected to the turret by means of bolts and cooperating vertically elongated slots, and said rest having

means which upon rotation of the turret on the column engages and raises the guard plates from their lower position to their position above the rest.

5 7. In a device of the character described, a rest, an indexing column secured to said rest and having a corrugated indexing base supported on said rest, a rectangular tool holding turret rotatably mounted on said column and having its lower portion provided with corrugations to engage and mesh with the corrugations of the indexing base, means to move said turret out of operative engagement with the indexing base, and guard plates carried by the lower portions of the sides of the turret, said plates being independently movable vertically from a position in which they extend below the top of the rest to a position in which they are disposed above the top of the rest, said guard plates being freely movable from their lower to their higher positions, and said rest having cam means which upon rotation of the turret on the column engages and raises the guard plates from their lower positions to their higher positions above the rest.

25 8. In a device of the character described, a rest having a rounded upper edge, an indexing column secured to said rest and having a corrugated indexing base supported on said rest, a rectangular tool holding turret rotatably mounted on said column and having its lower portion provided with corrugations to engage and mesh with the corrugations of the indexing base, means to move said turret out of operative engagement with the indexing base, and guard plates carried by the lower portions of the sides of the turret, said plates being independently movable vertically from a position in which they extend below the top of the rest to a position in which they are disposed above the top of the rest, said plates being connected to the turret by means of bolts and cooperating vertically elongated slots, the lower corners of each plate being shaped to form a cam surface for engaging the rounded upper edge of the rest to raise the plate from its lower position to a position above the rest when the turret is rotated about the column.

ARTHUR W. POREAU.
